UNITED STATES PATENT OFFICE.

RALPH J. OCHS, OF SAN BERNARDINO, AND CARL E. HODES, OF SAN FRANCISCO,
CALIFORNIA.

AUTO THEFT SIGNAL.

1,408,133.

Specification of Letters Patent. Patented Feb. 28, 1922.

Application filed October 1, 1920. Serial No. 414,036.

To all whom it may concern:

Be it known that we, RALPH J. Ochs and CARL E. Hodes, both citizens of the United States, residing, respectively, at San Bernardino, in the county of San Bernardino, State of California, and San Francisco, in the county of San Francisco, State of California, have jointly invented new and useful Improvements in Auto Theft Signals, 10 of which the following is a specification.

This invention relates to a bumping device, and particularly that form of bumping device which is adapted to be placed upon a vehicle wheel so that when the wheel is 15 rotated upon a roadway said device will come into contact with said roadway and tend to lift the wheel upwards and shake the vehicle to attract the attention of pedestrians. The invention is particularly applicable as an auto theft signal. The invention has for an object the provision of a bumping device which may be firmly secured to a wheel of the commercially known disc type. Another object is the provision 25 of a bumping device which may be attached to a wheel of any form and which when so placed on said wheel cannot be moved from its position without releasing the same properly.

30 In practicing the invention we provide a bumping device which includes oppositely bowed arms having upper ends directed toward each other, and the lower ends provided with projections.

35 The angularly directed portion of each arm is channeled so as to engage with a spoke or with outstanding bolt heads of a disc wheel. The said arms are pivotally joined to each other adjacent the projections used for bumping purposes, and a locking means is associated adjacent the pivot point. Each of the projections is outwardly flared or angled in such a manner that in 40 case the wheel is rotated and the projections come into contact with the roadway, all strain would be carried by the shouldered portion of the arms and by the bolt joining at the pivot point. By locating the lock member a little above or below the pivot

45 point of the said arms all strain due to rotating the wheel with the projections engaging the roadway could be released from the lock and consequently would never endanger or render the lock inoperative. It is 50 a known fault with the average theft signal that if the vehicle to which the same is

attached should be moved, that the auto theft signal upon engaging the roadway would tend to strain the lock member rendering it impossible to open said theft signal afterwards. 60

The invention has for further objects the provision of an improved bumping device which will be superior in point of relative simplicity and inexpensiveness of construction and organization, taken in conjunction with positiveness and effectiveness in operation, and general efficiency and serviceability. 65

The invention further consists in the 70 novel and useful provision, combination, construction, relative arrangement, mode of operation and inter-relation of parts, members and features, all as hereinafter described, shown in the drawing and finally 75 pointed out in claims.

In the drawing:

Figure 1 is a fragmentary side elevation of a vehicle wheel of the commercially known disc type with the improved bumping device shown in position thereon; 80

Figure 2 is a plan view of the bumping device;

Figure 3 is a top plan view of the bumping device shown in Figure 2 and taken 85 on the line x^3-x^3 , Figure 2, and looking in the direction of the appended arrows;

Figure 4 is a fragmentary plan view, certain parts being shown in section, of means for locking the respective arms of the bumping device; said view showing the lock in 90 operative position;

Figure 5 is a view similar to Figure 4 but showing the locking member in inoperative position taken on line x^5-x^5 Figure 6; 95

Figure 6 is a cross sectional view taken on the line x^6-x^6 , Figure 2, and looking in the direction of the appended arrows; and,

Figure 7 is a fragmentary plan view, certain portions being sectioned, of the improved bumping device shown in cooperation with the bolt portions of a disc wheel. 100

Corresponding parts in all the figures are designated by the same reference characters.

Referring with particularity to the drawing, the improved bumping device A includes arm members B each of which is provided with means C adapted to be presented to the roadway. A lock member D 110 is likewise carried by the arms B. Each of the arms B is provided at one end as at 1

with an angularly directed portion, such angularly directed portion being formed with a channel 2, on one of the arms and with a chamber 2^a on the other arm which 5 channel and chamber as shown in Figure 7, is adapted to confine the ends of a bolt 3 extending through the disc 8 of a disc wheel 5. While the angularly directed portion 1 may be channeled as shown at 2 it is preferable to enlarge the head portion so as to 10 have a bore therein, and to leave the opposite angularly directed portion bifurcated or channeled as shown; thus when the device A is upon a wheel it would be impossible 15 to remove the same because of its grasping qualities upon the bolt ends. The arms B are each outwardly bowed as at 6 so as to 20 form an annulus between the same so that the said arms may be adapted to extend 25 around a tire 7 of the wheel. The angularly directed portion 1 engages opposite faces of the disc 8 located within the circumference of the wheel. It is obvious that the 30 channeled portion 2 will securely engage the bolt ends 3 and prevent movement of the device A when it is in position upon the wheel as shown in Figure 1. Furthermore, the channeled portion 2 might readily engage the spokes of a wheel in place of the 35 bolts on a disc wheel.

Referring to Figure 6 it will be observed 40 that one of the arms B, as at 9, is provided with spaced cheeks 10 and 11 and that the other arm as at 12, is provided with a tongue 45 portion 13 fitting between said cheeks 10 and 11. A bolt 14 passes through a perforation extending through the cheeks and the tongue for holding the arms B in relation to each other, and likewise so that the 50 arms B may be relatively movable. It will be seen by referring to Figure 2, as well as Figure 6, that the cheeks 10 and 11 are outwardly curved as at 15. The opposite arm B which carries the tongue 13 is so formed 55 that the shouldered portions of the same as 16 and 17 are correspondingly curved to the portion 15 so that when any weight or pressure is exerted against the member C, the cheeks 10 and 11 will engage the portions 16 and 17 and tend to prevent strain at 60 the pivot point, likewise taking all stress from the lock member. The means C associated with each arm B is so arranged that when the members are joined at the pivot 65 point the means C subtend an angle α between the same, while the extremities of said means C as at 18 and 19 are located outwardly from the pivot point. The result is that if the means C come into contact with the roadway, the pressure being 70 exerted at the points 18 and 19 will tend to revolve the arms B inwardly so as to more tightly grip either the spoke of the wheel or the opposite faces of the disc in 75 case the wheel is a disc wheel.

The lock member is illustrative only, and we do not wish to be restricted to the particular form of lock shown; however, in Figures 4 and 5 one of the arms B as 20 acts as a lock-carrying member, while the other arm acts as a lock-receiving member. The lock D includes the usual opening 21 through which a key may be passed for operating the lock. One of the arms B as shown at 20 is provided with a bore or socket 22 within which socket is confined a coil spring 23. A bolt 24 is normally confined within the bore 22 and engages at one end as 25 with an end of the spring 23. The opposite arm B as at 26 is provided with a socket which 30 is adapted to receive an end of the bolt 24 when the sockets 22 and 26 are in registration. Such a registration will occur when the device A is in operative position, or in a position upon the vehicle wheel as shown 35 in Figure 1. The bolt 24 is provided with a notched portion 27 and a stud 28 associated with the rotatable portion of the lock D may engage the notched portion 27 and tend to retract the bolt 24 from the socket 26 so 40 that the arms B may be rendered relatively movable and the entire device A removed from a vehicle wheel. It is obvious that the particular arrangement shown will allow the device A to be snapped into position 45 without operating the lock with a key each time. It will also be observed that the bolt 24 is located in the drawing below the pivot point, although it may as readily be located above the pivot point. The particular 50 method of joining the arms B below the pivot point tends to relieve all strain from the bolt 24 in case, as has been pointed out, of rotation of the vehicle wheel with the device A in position thereon. It is obvious 55 that the spring member 23 will normally urge the bolt 24 outwardly so that the bolt may be at all times ready to be shot into the socket 26 when the arms B are in proper 60 position.

It will be seen that this bumping device 65 differs from the forms now on the market, in that it provides means for engaging the opposite face of a disc wheel or for engaging a spoke of a spoke wheel. This particular bumping device overcomes faults incident to the commonly known forms now 70 on the market, by positively offering means whereby it is impossible to loosen the said bumping device from the wheel by, say, deflating the tire. The device is likewise novel 75 in that it provides for a stress-resisting means; a means for removing all stress from the lock member and further, for an arm that does not entirely surround the rim of 80 a wheel so that the bumping device is applicable to any known form of wheel now on the market, but is particularly adaptable to the disc wheel type.

It is obvious that many changes and modi- 85

fications may be made in practicing the foregoing invention, all, however, without in any manner departing from the true spirit of the invention in adapting it to varying 5 conditions and requirements of use and service.

Having thus disclosed our invention, we claim and desire to secure by Letters Patent:

1. A device of the character disclosed, including two outwardly bowed arms pivotally joined together so as to be relatively movable; each of said arms being provided at one end with an outwardly flared projection adjacent the pivotal connection, their opposite ends being angularly directed toward each other, and means for locking said arms in work-engaging relation.

2. A device of the character disclosed, including two outwardly bowed arms pivotally joined together so as to be relatively movable; each of said arms being provided at one end with an outwardly flared projection adjacent the pivotal connection, their opposite ends being angularly directed toward each other, and means for locking the said arms in work-engaging relation; one of said angularly directed ends being formed with a channel.

3. A device of the character disclosed, including two outwardly bowed arms pivotally joined together so as to be relatively movable; each of said arms being provided at one end with an outwardly flared projection adjacent the pivotal connection, their opposite ends being angularly directed toward each other, and means for locking the said arms in work-engaging relation; one of said angularly directed ends being formed with a channel, and the angularly directed end of the other arm being provided with a chambered portion.

4. A device of the character disclosed, including two outwardly bowed arms pivotally joined together so as to be relatively movable; each of said arms being provided at one end with an outwardly flared projection adjacent the pivotal connection, their opposite ends being angularly directed toward each other, and means for locking the said arms in work-engaging relation; one of said angularly directed ends being formed with a channel, and the angularly directed end of the other arm being provided with a chambered portion; said locking means being adjacent the pivotal connection of the arms.

5. A device of the character disclosed, in-

cluding two outwardly bowed arms, each of which is provided with an outwardly flared projection, one of said arms being formed with two spaced cheeks and the other arm being provided with a tongue portion received between said cheeks, the said pivotal connection being through said cheeks and said tongue; there being a locking means for maintaining said arm members in work-engaging relation, said locking means being adjacent said pivotal connection whereby when pressure is exerted against the outwardly flared projection all strain is relieved from the pivot point and locking means by 70 the cheek members engaging the shouldered portion surrounding the tongue member of the oppositely bowed arm.

6. A device of the character disclosed, including two outwardly bowed arms, each of which is provided with an outwardly flared projection, one of said arms being formed with two spaced cheeks and the other arm being provided with a tongue portion received between said cheeks, the said pivotal 80 connection being through said cheeks and said tongue; there being a locking means for maintaining said arm members in work-engaging relation, said locking means being adjacent said pivotal connection whereby 85 when pressure is exerted against the outwardly flared projections all strain is relieved from the pivot point and locking means by the cheek members engaging the shouldered portion surrounding the tongue 90 member of the oppositely bowed arm; the end opposite the projection of one of said bowed arms being angularly directed toward an angularly directed portion on the opposite bowed arm, one of said angularly directed ends being provided with a vertical slot and the other angularly directed end of the other bowed arm being provided with a chambered portion, whereby the device may either engage a bolt head or a spoke of a 100 wheel.

In testimony whereof, we have signed our names to this specification in the presence of two subscribing witnesses:

RALPH J. OCHS.

CARL E. HODES.
